[57] CLAIM

The ornamental design for a bracelet, as shown and described.

DESCRIPTION

FIG. 1 is a perspective view of the front and top of a bracelet showing my new design;

FIG. 2 is a front elevational view thereof;

FIG. 3 is a rear elevational view thereof;

FIG. 4 is a side elevational view of one side thereof, the opposite side being a mirror image thereof; and,

FIG. 5 is a top plan view thereof, the bottom being a mirror image thereof.

The interior surface of the bracelet is plain and unornamented.
